INVENTOR

S. R. Stinard

United States Patent Office.

STEPHEN R. STINARD, OF PATERSON, NEW JERSEY.

Letters Patent No. 96,051, dated October 19, 1869.

IMPROVED RAILWAY-CAR BRAKE.

The Schedule referred to in these Letters Patent and making part of the same.

To all whom it may concern:

Be it known that I, STEPHEN R. STINARD, of Paterson, in the county of Passaic, and State of New Jersey, have invented a new and useful Improvement in Operating Car-Brake; and I do hereby declare that the following is a full, clear, and exact description thereof, which will enable others skilled in the art to make and use the same, reference being had to the accompanying drawings, forming part of this specification.

This invention relates to improvements in operating brakes for retarding or stopping railroad-cars or trains of cars, having particular reference to brakes which are made to act by means of steam or compressed air, or other elastic fluid, and which are under the control of the engineer, but at the same time not interfering with the operation of the hand-brake of each car; and

The invention consists in the combination of devices for taking up or compensating for the "slack" or play between the cars of a train, as will be herein-after more fully described.

In the accompanying plate of drawings—

Figure 1 represents a sectional side elevation of two cars, showing the mechanism by which I accomplish my object, the section being through the line $x x$ of fig. 2.

Figure 2 is a view of the under side of the two cars, giving a plan view of the mechanism.

Similar letters of reference indicate corresponding parts.

In operating car-brakes from the engine, by means of the application of steam, a great difficulty has hitherto constantly intervened to render this method but little, if at all, superior to the old or hand-brake system.

This difficulty arises from the time and expenditure of power required to take up the slack of the system of brake connecting-rods, which, in a long train of cars, amounts to many feet; that is to say, while it is necessary that there should be a certain amount of "play" between the cars. This involves proportionate increase of length of the rods or chains which connect the brakes of the respective cars, and when the engineer "brakes up" the locomotive or the whole train, the several cars crowd upon each other, and thus occasion "slack" in the aforesaid rods or chains, which must be taken up, and thus much time is lost which in an emergency, or in case of great danger, might be invaluable.

To obviate this and other difficulties arising from the same cause is the object of my invention.

In carrying it out, I connect two cars, A B, in the ordinary way.

Between the trucks of each depends a rectangular frame, A'.

A stout rod, D', slides longitudinally in arms or brackets of this frame, and to its centre is secured one end of a chain or cord, a, which passes between friction-rollers, and is connected with the levers c and c', which are all pivoted in the frame A', as shown in fig. 1.

Each car may be provided with a hand-brake, arranged at one or both ends thereof, and connected with the steam-brake mechanism at C, by means of a chain, shown in red.

Upon operating the hand-brake standard, the chain a will draw together the free ends of the levers c c', and thereby apply or operate the brake-beams J, through the medium of the levers d d and connecting-rods e e e' e'.

It will be seen that the upper ends of levers d d are connected to the frame of the car by rods i i. In this operation each of the rods D' serves no other purpose than convenient means of attachment for one end of each of the chains a a, whereby to obtain a leverage to actuate the levers c c', or, in other words, were the chains a a attached to the lower horizontal bars of the frame A', the effect would be the same.

In the operation of applying the brakes by steam, these rods are, however, a main feature, as will now be made apparent.

On each end of the rods D' is pivoted a short sway-bar, E.

One end of this sway-bar is connected by a rod, G, with the lower end of a lever, F, which has its fulcrum in a bracket at the end of the car, and is connected at its upper end with the sliding bumper-head R, by a rod, m.

The other end of each sway-bar is connected with that on the car opposite, by means of a rod, D, as in fig. 2. (It will be observed that the rod is placed in a diagonal position.)

Each rod D is jointed at H, to permit the cars to be disconnected, and any suitable device may be employed to suspend each half of the rods when this is effected.

All the cars of the train are connected like those shown in the drawing.

Any preferred arrangement of means or devices under the control of the engineer may be employed in connection with the locomotive for "winding up" the brakes.

The operation of the system of sway-bars and rods is as follows:

A winding-cord or chain is provided to connect that one of the rods D' which is attached to the car nearest the locomotive, which we will suppose to be the car A. When the power is applied on the locomotive, the rod D' on the nearest car will be drawn in the direction of the line of motion. This will occasion corresponding

movement of the sway-bar at its rear end, and also throw it into a diagonal position, and thus the succeeding sway-bars E and rods D and D' will be moved in the direction of the line of motion, and said sway-bars also assuming a diagonal position. Meantime the speed of the engine being slackened, the cars crowd upon one another, and the bumper-heads being pressed in, the rods m operate the levers F F', throwing their lower ends outward from the ends of the car, or toward each other, and thus, through the connecting-rods G, tending to restore the sway-bars to their position at right angles to the line of motion.

The greater the tension imparted by the winding-mechanism, the more will the bumper-heads be pressed together, and thus corresponding tension be exerted on the sway-bars E and rods D, D', and G.

It is evident that by removing the rods G and levers F, and connecting the rods D directly with the rods D', no or very slight effect could be produced upon the brakes of any car succeeding that which is coupled with the locomotive, since the "slack" between even two cars would be so great as to exceed the stretch of the ropes or chains a, which, by the move-

ment of the rods D', are caused to operate the levers c c', as in the case of the hand-brake.

A more flexible connection may be substituted for the rods D with equally good results.

Having thus described my invention,

What I claim as new, and desire to secure by Letters Patent, is—

1. The combination of the rods D, D', and G, sway-bars E, and levers F, with the brake-beams of a railroad-car, substantially as hereinbefore shown and described, for the purpose specified.

2. In combination with rods D, D', and G, sway-bars E, and levers F, the mechanism seen at C, substantially as hereinbefore shown and described.

3. In combination with the elements of the second claim, the brake-staff chain, as specified.

The above specification of my invention signed by me, this 9th day of June, 1869.

STEPHEN R. STINARD.
